 Pump and Machinery Corporation, Harrison,
 N. J., a corporation of Delaware

Application October 24, 1939, Serial No. 300,922

4 Claims. (Cl. 62—115)

This invention relates to refrigerating systems, and more particularly to refrigerating systems wherein a volatile refrigerant such as "Freon" is employed in a closed circuit for cooling or chilling a cooling medium such as water, air or the like. An object of the present invention is to provide a closed refrigerating system which will require a minimum amount of volatile refrigerant to provide the desired cooling, thus not only lowering the initial cost of refrigerant but also reducing the cost of recharging the system with the refrigerant if it becomes necessary to do so.

Another object of the present invention is to provide a closed refrigerating system in which the volatile refrigerant is constantly in circulation, providing cooling in the evaporator by showering therethrough and consequently maintaining the pressure in the evaporator at a low value due to the absence of accumulated refrigerant therein.

A further object of the present invention is to provide in a refrigerating system as above set out a novel type of pump for circulating the refrigerant which pump embodies a relatively large suction chamber acting in effect as an accumulator for the liquid refrigerant and always maintaining the proper head on the pump. The suction chamber of the pump opens into the driver or motor housing of the pump, which housing is in turn connected in the refrigerating system at a point in advance of the suction of the compressor of the system, whereby the evaporation of the refrigerant in the suction chamber of the pump will circulate through the motor housing, serving as a cooling medium for the motor and being compressed by the compressor, returning actively into the system.

With these and other objects in view, as may appear from the accompanying specification, the invention consists of various features of construction and combination of parts, which will be first described in connection with the accompanying drawings, showing a refrigerating system of the preferred form embodying the invention, and the features forming the invention will be specifically pointed out in the claims.

In the drawings:

Figure 1 is a diagrammatic view, partly in section, of the refrigerating system.

Figure 2 is a vertical section through the refrigerant circulating pump.

Referring more particularly to the drawings, the evaporator 1 is of any approved type of shell evaporator having a plurality of longitudinally extending tubes 2 therein through which the wa- ter, air or other cooling medium to be chilled is

circulated, entering the evaporator through the inlet 3 and leaving the evaporator through the outlet 4. In the drawings the evaporator is shown as a multiple pass evaporator for the cooling medium circulating through the tubes, but it is to be understood that any arrangement of tubes or passes found practical may be employed without departing from the spirit of the present invention.

The volatile refrigerant, such as "Freon" or the like, is sprayed or showered into the top of the evaporator 1 through a plurality of spraying heads 5 and it showers downwardly across the tubes 2.

The volatile refrigerant, after passing across the tubes 2 of the evaporator 1, passes into a collection well 6 and the system is charged and controlled, as will be hereinafter more specifically pointed out, to maintain the refrigerant liquid level at approximately the top or inlet of the collection well 6 so as to prevent accumulation of 20 the liquid refrigerant in the evaporator.

The refrigerant collecting well 6 is connected by a conduit 7 to the suction chamber 8 of the circulating pump structure 9.

As clearly shown in the drawings, the suction chamber 8 of the circulating pump structure 9 is quite large relative to the apparatus in the system, and is positioned so that when the liquid refrigerant therein seeks its level with the liquid refrigerant in the collection well 6 a space indicated at 10 will be provided in the suction chamber 8 above the level of the liquid refrigerant therein.

The suction chamber 8 serves as an accumulator for the liquid refrigerant and maintains a proper head on the impeller 11 of the pump structure. The pump impeller 11 discharges the liquid refrigerant through the discharge volute 12 of the pump casing 13 and through the conduit 14 into the header 15. The spray heads 5 are connected to and receive the liquid refrigerant from the header 15.

The volatile refrigerant which evaporates in the suction chamber 8 of the pump structure 9, together with a part of the volatile refrigerant which evaporates in the evaporator 1 and enters the space 10 through the by-pass pipe 16, passes upwardly through the openings 17 into the motor housing 18. The motor 19 within the housing 18 is connected to and drives the impeller 11 through the medium of the relatively long shaft 20, which passes axially through the suction chamber 8.

The motor housing 18 has a pipe 21 connected to the top thereof, which pipe has its outlet 55

opening connected in the line or pipe 22 between the compressor 23 and the interior of the evaporator 1. The compressor 23 draws the gaseous or evaporated refrigerant from the interior of the evaporator 1 through the line 22 and draws it through the motor housing 18 through the pipe 21, thus causing a circulation of gaseous refrigerant through the motor 19 for the purpose of cooling the motor. The gaseous refrigerant 10 pressed by the compressor 23 is discharged into the refrigerant condenser 24 from which it passes through a trap 25 and connection 26 to the header 15.

The trap 25 also serves as an accumulator for 15 liquid refrigerant from the condenser, and it has a float actuated valve 27 therein which is opened when the level of refrigerant in the trap 25 reaches a predetermined height so as to permit make-up liquid refrigerant to pass to the header 20 15 for conjunction with the refrigerant delivered thereto by the pipe 14 for passage through the evaporator 1. The float valve structure 27 is set to admit liquid refrigerant to the header 15 only at such time as the quantity of refrigerant actively circulated by the pump 9 through the header 15 and spray heads 5 is diminished below a predetermined quantity, so that the quantity of the refrigerant actively passing through the evaporator 1 will always be controlled to maintain the proper chilling action in the evaporator 30 and to prevent accumulation of liquid refrigerant in the evaporator.

It will be understood that the invention is not to be limited to the specific construction or arrangement of parts shown, but that they may be widely modified within the invention defined by the claims.

What is claimed is:

1. In a refrigerating system in which a volatile liquid refrigerant is evaporated, compressed and condensed, the combination, of an evaporator, a refrigerant pump for circulating volatile liquid refrigerant through the evaporator having a suction chamber, a compressor for compressing the refrigerant vapor, a motor for driving said circulating pump, a housing for said motor open to said suction chamber of said pump for receiving refrigerant vapor therefrom for cooling said mo-

tor, and a connection from said housing to said compressor.

2. In a refrigerating system in which a volatile liquid refrigerant is evaporated, compressed and condensed, the combination, of an evaporator, a refrigerant pump for circulating volatile liquid refrigerant through the evaporator, a compressor for compressing the refrigerant vapor, a motor for driving said circulating pump, a housing for said motor, a connection between said motor housing and said evaporator for delivering refrigerant vapors to the motor housing, and a connection between said motor housing and the suction of said compressor.

3. In a refrigerating system in which a volatile liquid refrigerant is evaporated, compressed and condensed, the combination, of an evaporator, a refrigerant pump for circulating volatile liquid refrigerant through the evaporator and having a relatively large suction chamber, a motor for driving said circulating pump, a housing for said motor open to said suction chamber and receiving refrigerant vapor therefrom for cooling said motor, a connection between said motor housing and said evaporator for receiving refrigerant vapor therefrom, and a connection between said motor housing and said compressor suction whereby the suction action of the compressor will create a circulation of the evaporated refrigerant through the motor housing.

4. In a refrigerating system in which a volatile refrigerant is evaporated, compressed and condensed, the combination, of an evaporator, a refrigerant pump for circulating volatile liquid refrigerant through the evaporator and having a relatively large suction chamber, a driving motor for said circulating pump, said suction chamber being located between the pump and the driving motor and of such area as to provide an evaporation space in the suction chamber above the normal liquid level therein, a housing for said motor open to said vaporizing space in said suction chamber for receiving refrigerant vapor therefrom for circulation through said motor housing, and a connection between said motor housing and the suction of said compressor for drawing the refrigerant vapor through said motor housing.
